Primary Examiner—Jeffrey Asch

(74) Attorney, Agent, or Firm—Banner & Witcoff, Ltd.

(57) **CLAIM**

We claim the ornamental design for a key button for a handset, as shown and described.

DESCRIPTION

FIG. 1 is a front view of the key button for a handset; and, FIG. 2 is a perspective front view thereof.

The broken line showings throughout the drawing views are for illustrative purposes only and form no part of the claimed design.
